UNITED STATES PATENT OFFICE.

FRANCIS L. KIRBY, OF GLOBE, ARIZONA, ASSIGNOR OF ONE-THIRD TO HENRY L. TAYLOR, OF GLOBE, ARIZONA, AND ONE-THIRD TO THEODORE T. SWIFT, OF SAFFORD, ARIZONA.

SIFTER.

1,245,595.

Specification of Letters Patent.

Patented Nov. 6, 1917.

Application filed June 6, 1916. Serial No. 102,001.

To all whom it may concern:

Be it known that I, FRANCIS L. KIRBY, a citizen of the United States, residing at Globe, in the county of Gila and State of Arizona, have invented new and useful Improvements in Sifters, of which the following is a specification.

The invention relates to sifters, and is more especially designed for sifting flour.

10 The primary object of the invention is the provision of a sifter of this character wherein the body thereof has arranged therein a plurality of sieves disposed in superposed relation and agitators which co-operate with the sieves to prevent packing or clogging of the material and also for cutting or breaking the lumps which may be in the material.

Another object of the invention is the 20 provision of a sifter of this character wherein the necessity of separate and distinct sifting operations is eliminated as the plurality of sieves will act upon the material so as to thoroughly sift the same in a single 25 operation of the sifter with despatch.

A further object of the invention is the provision of a sifter of this character wherein the sediment from the sieves can be readily dumped or discharged therefrom 30 through a side opening of the body of the sifter, which opening is normally closed through the medium of a slide, and in this manner the sifter can be conveniently cleaned after the use thereof.

35 A still further object of the invention is the provision of a sifter of this character which is simple in construction, thoroughly reliable and efficient in operation, strong, durable and inexpensive in manufacture.

40 Other objects will be in part obvious and in part hereinafter set forth.

The invention accordingly consists in the features of construction, combination of elements and arrangement of parts which will 45 be exemplified in the construction hereinafter described, and the scope of the application of which will be indicated in the appended claim.

In the accompanying drawings:

50 Figure 1 is a side elevation of a sifter constructed in accordance with the invention;

Fig. 2 is a vertical longitudinal sectional view thereof;

55 Fig. 3 is a top plan view;

Fig. 4 is a side elevation of the uppermost agitator.

Similar reference characters indicate corresponding parts throughout the several views of the drawing.

Referring to the drawing in detail, A designates the cylindrical body or casing of the sifter which is of the appropriate or convenient size and is formed exteriorly thereof, as is usual, with a suitable handle 60 B for the holding of the sifter when in use. Provided in the body A circumferentially thereof are spaced grooves or channels 5 in which are fitted the rims 6 of sieves 7 which, in this instance, are preferably three in 70 number, and which is made from wire mesh. The mesh of the respective series of sieves can be varied should the occasion require, and these rims 6 thereof are suitably fastened in place interiorly of the body or 75 casing of the sifter.

Mounted on the upper end of the body or case A is a triple brace 8 having journaled centrally therein an agitator stem or shaft 9 which is passed downwardly centrally through the series of sieves 7, while the upper end of the stem or shaft is formed with a crank 10 carrying a loose knob 11 so that it can be conveniently turned for the rotation of the stem or shaft 9 which 80 has fitted thereon the agitators 12, 13 and 14 respectively, the sieves 7 being each of substantially hemispherical shape or concaved at their inner sides, and the agitators are bowed similarly to the shape of the sieves 85 so as to work against the concaved surfaces thereof for preventing the clogging of said sieves with the material and also for breaking up the lumps in the material.

The agitator 12 has connected with its 90 limbs the curvilinear wires 15 which travel in different paths with respect to each other and follow one another in a corkscrew motion, the trend of the wires being designed by reason of their particular shape so as 100 not to follow in the same radius and by the motion thereof serve to force downwardly the material through the uppermost sieve within the body or casing A of the sifter.

Formed in the side of the body or casing 105 A is an opening 16 which is normally closed through the medium of a gate or slide 17, the same being engaged with ears 18 cut and stamped from the body or casing A as shown, and this slide or gate has a finger 110

hole 19 thereon so that it can be opened and closed, the opening 16 being placed relative to the sieves 7 so that the residue or sediment can be readily discharged therefrom through the opening in the sifter for the cleaning thereof.

It will be noted that when the sifter is in use and operated that there is required but a single operation thereof for the proper sifting of the material, such as flour, and thereby eliminating the necessity of several operations of the sifter for the repeated sifting of the material as is usual, which is usually required in recipes for cooking. The material will be thoroughly sifted when the agitators are set in motion, as these agitators coöperate with the sieves 7 and precipitate the material therethrough.

From the foregoing description, taken in connection with the accompanying drawing, the construction and operation of the herein described sifter will be readily ap-

parent and, therefore, a more extended explanation has been omitted.

Having thus described my invention, I claim:

An agitator for sifters including a shaft, adapted to be mounted for rotation, and a series of arms extending from the shaft in pairs, the arms of each pair constituting a concave formation vertically of the shaft and an S-form curve horizontally of the shaft and wires corresponding in number to the number of arms and secured by their upper ends to the shaft above the arms projected from the shaft on curved lines approximately concentric outwardly and downwardly, with the end of each wire projected from the shaft to the arm on a gradual increasing radius, with such curve in opposition to the horizontal curvature of the arm to which it connects.

In testimony whereof I affix my signature.

FRANCIS L. KIRBY.
